(57) CLAIM

The ornamental design for a transparent chef's knife holder, as shown and described.

DESCRIPTION

FIG. 1 is a perspective view of one embodiment of my new design for a transparent chef's knife holder;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan view thereof;

FIG. 7 is a front elevational view thereof, the knife shown in phantom being no part of the design;

FIG. 8 is a perspective view of a second embodiment of my design;

FIG. 9 is a left side elevational view of the second embodiment;

FIG. 10 is a right side elevational view of the second embodiment;

FIG. 11 is a rear elevational view thereof;

FIG. 12 is a top plan view thereof;

FIG. 13 is a bottom plan view thereof; and,

FIG. 14 is a front elevational view thereof, the knife shown in phantom being no part of the design.
